UNITED STATES PATENT OFFICE

2,663,080

AUTOMATIC BLADE HOLDING RAZOR

Ernest T. Yonamine, Honolulu,
Territory of Hawaii

Application October 29, 1951, Serial No. 253,578

5 Claims. (Cl. 30—40)

1

This invention relates to a combined razor and blade changer wherein a supply of blades is retained in the handle and in which blades are changed by a simple pull-push operation.

An object of this invention is to provide a razor and blade changer of the character described which uses double edge as well as single edge blades and which employs a novel releasable locking means for holding a blade in proper position on the shaving ledge opposite the handle.

A further object of the invention is to provide a razor and blade changer which is easy to load, easy to operate and change blades, sturdy and attractive.

These, together with various ancillary objects and features of the invention which will later become apparent as the following description proceeds, are attained by the device, a preferred embodiment of which has been illustrated, by way of example only, in the accompanying drawings, wherein:

Figure 1 is a perspective view of the device;

Figure 2 is a sectional view taken on the line 2—2 of Figure 1;

Figure 3 is a sectional view similar to Figure 2 illustrating a different operating position;

Figure 4 is a sectional view taken on the line 4—4 of Figure 3;

Figure 5 is a sectional view taken on the line 5—5 of Figure 3;

Figure 6 is a sectional view taken on the line 6—6 of Figure 4;

Figure 7 is a perspective view of the device with the housing shown in dotted lines to illustrate details of construction;

Figure 8 is a perspective view in reversed position of the blade receiving plate and shaving ledge;

Figure 9 is a group perspective view of the blade magazine and cover therefor;

Figure 10 is a perspective view of the blade guide and holder;

Figure 11 is a perspective view of the cam latch or lock;

Figure 12 is a perspective view of the magazine actuating bar; and

Figure 13 is an enlarged detail perspective view of one corner of the ejector plate.

Specific reference will now be made to the drawings. In the several views, in the accompanying drawings and in the following specification, similar reference characters indicate corresponding elements throughout.

Indicated generally at 10 is a housing, preferably plastic, which constitutes the handle of the

2

present device which is open at its rear end as at 14. The front end 16 is substantially closed except for the provision of a slot adjacent the top for receiving several parts of the invention, as will appear hereinafter. The substantially rectangular case 18 constitutes a magazine in which blades 20 are received and urged upwardly by means of a spring finger 22 therein. The upper longitudinal edges of the magazine are provided with inturned longitudinal channels 24 which slidably receive a closure 26 so that the magazine serves as a self-contained package for the blades. These channels serve another purpose after removal of the closure as will appear hereinafter. To properly place the magazine in the housing, the closure slides out when the magazine is placed on an elongated bar 28, Fig. 12, which has an upstanding short leg 30 engaging the front end of the magazine and an upstanding long leg 32 engaging the rear end. The lip 34 serves as a handle whereby the bar and magazine thereon are pushed into the handle housing 10 through its open end as shown clearly in the drawings.

Positioned in the housing on the top of the magazine is an elongated member 36 which is in the form of a relatively flat tube having a depressed shaving ledge 38 at one end. One side of this tube is cut out as at 40 to receive a blade urged therein from the magazine which it overlies and the sides of this tube include longitudinally extending lateral flanges 42 slidably received in the channels 24 of the magazine. The tube at its blade discharge end 44 has a transverse depending lug or flange 46 which engages the front end of the magazine to properly position the same in the housing. Slidably in the tube is a blade ejector plate 48 having an inner blade contacting edge 50 configurated to conform with one edge of the blade 20. As a blade is urged by the ejector plate through the discharge opening 44 on the shaving ledge 38, the ejector plate may be releasably held in this position to cover the open upper end of the magazine by a detent 52 at one end of the ejector plate engageable in a recess 54 in the flat tube 36.

The shaving ledge 38 is constructed of a flat blade, retaining platform 56 with depending side members 58, the forward edges of which include extensions 60 having transversely aligned apertures 62. Adjacent the forward extensions, the platform is provided with a pair of longitudinal slots 64 for a purpose soon to appear. An elongated blade and guide holder 66 is provided which includes an elongated shank 68 having a longi-

tudinal ridge 70 engageable in the conventional longitudinal slot 72 of the blade 28. The rear of the shank includes an enlarged flat triangular head 74 having a rounded edge 76 which is received in the blade outlet 44. The forward end of the shank includes an enlarged triangular flat head 78 having depending legs 80 and longitudinally extending lugs 82 having gripping grooves 84. The legs 80 extend through the longitudinal slots 64 as shown clearly in Figures 4 and 7. A 10 cam latch or lock 86 is provided in the form of a V-shaped member, the apex 90 of which is rounded. One leg 92 of the cam latch is substantially flat and includes a laterally extending handle 94, whereas the other leg 98 includes, adjacent the apex, lateral trunnions 98 journaled in the apertures 62.

In operation, the slide 48 is depressed to release the detent 52 from the recess or slot 54 and then pulled out to the position shown in Figure 3. This 20 uncovers the magazine and the spring 22 therein urges the topmost blade into the blade-receiving opening 48. The ejector slide is then pushed inwardly as shown in Figure 2 whereby the blade is pushed out through the opening 48 beneath 25 the head 74 onto the ledge 38 being guided in position thereon by the ridges 78 and the legs 80. By urging the cam latch 86 downwardly and into the position shown in Figure 2, the rounded apex 90 wedges the outer edge of the blade against the flat 30 head 78 and locks it in place. To change blades, the cam lock is pivoted upwardly as shown in Figure 3 to release the blade, after which a pull-push on the ejector plate or slide 48 will push out a blade on the shaving ledge, the new blade forcing the old blade off the ledge. The cam latch is then closed again and one can begin shaving, using the plastic housing 10 as a handle.

In view of the foregoing description taken in conjunction with the accompanying drawings, it 40 is believed that a clear understanding of the device will be quite apparent to those skilled in this art. A more detailed description is accordingly deemed unnecessary.

It is to be understood, however, that even 45 though there is herein shown and described a preferred embodiment of the invention, the same is susceptible to certain changes fully comprehended by the spirit of the invention as herein described and within the scope of the appended 50 claims.

Having described the invention, what is claimed as new is:

1. A blade changing razor comprising a housing, a magazine in said housing, blades in said magazine and a resilient means urging said blades upwardly, an elongated member secured on the top of said magazine and having a portion extending beyond one edge thereof constituting a shaving ledge, said elongated member having a recess 60 therein above said magazine for receiving a blade urged thereinto, an ejector plate slidable in said elongated member and adapted to push a blade from said recess onto said shaving ledge, and means for releasably retaining a blade on said 65 shaving ledge, said magazine including longitudinally extending channels at the opposite upper side edges thereof, and longitudinally extending flanges on the opposite sides of said elongated member slidably engaging said channels.

2. A blade changing razor comprising a housing, a magazine in said housing, blades in said magazine and a resilient means urging said blades upwardly, an elongated member secured on the top of said magazine and having a portion extending beyond one edge thereof constituting a shaving ledge, said elongated member having a recess 5 therein above said magazine for receiving a blade urged thereinto, an ejector plate slidable in said elongated member and adapted to push a blade from said recess onto said shaving ledge, and means for releasably retaining a blade on said shaving ledge, said last-named means including an elongated blade guide and holder extending longitudinally across said shaving ledge and a cam latch pivoted on the free end of said ledge and adapted to wedge said blade guide and holder against a blade on said shaving ledge.

3. The combination of claim 2 wherein said ledge includes longitudinally extending slots through the free end thereof, said guide and holder including a shank having a longitudinal ridge adapted to engage in a blade recess, a flat head carried by said shank and legs depending from said head and passing through said slots.

4. The combination of claim 3 wherein said leg of said guide and holder includes rearwardly extending lateral lugs having gripping surfaces and said cam latch is a substantially V-shaped body having a rounded apex, one leg of said V-shaped body engaging said gripping surfaces of said lugs to urge said apex into engagement with the blade and wedge it against said flat head, said V-shaped body being pivoted for vertical movement to said ledge adjacent said apex.

5. A blade changing razor comprising a housing, a magazine in said housing, blades in said magazine and a resilient means urging said blades upwardly, an elongated member secured on the top of said magazine and having a portion extending beyond one edge thereof constituting a shaving ledge, said elongated member having a recess therein above said magazine for receiving a blade urged thereinto, an ejector plate slidably in said elongated member and adapted to push a blade from said recess onto said shaving ledge, and means for releasably retaining a blade on said shaving ledge, said magazine including longitudinally extending channels at the opposite upper side edges thereof, and longitudinally extending flanges on the opposite sides of said elongated member slidably engaging said channels, said elongated member consisting of a substantially flat tubular body, said ejector plate being slidably in said tubular body and including detent means for releasably retaining said ejector plate in a position covering said magazine.

ERNEST T. YONAMINE.
